TRAVERSE MECHANISM FOR GRINDING
MACHINES AND THE LIKEMorgan Fairest, Sheffield, England, assignor to
Morgan Fairest Limited, Sheffield, EnglandApplication January 27, 1948, Serial No. 4,513
In Great Britain January 27, 1947

8 Claims. (Cl. 51—233)

1

This invention relates to traverse mechanisms for grinding machines and the like, and has particular reference to traversing the work slides in machines for grinding the blades of table knives, carving knives, garden and other shears, scissors, and similar articles of cutlery, although the invention is also applicable to such purposes as traverse mechanisms for surface grinders, millers, planers, plano-millers, plano-grinders, and sliding and surfacing traverses of lathes.

In grinding cutlery, it is usual to grind the face (or, in the case of table and similar knives, both faces in turn) as an operation in which the blade is rapidly fed idly in an inwardly oblique direction across one side of a cup-wheel, the face of which is hollow to form a conical surface to impart the desired slightly rounded face to the face of the blade; the blade is then moved into contact with the wheel, given a dwell while the wheel grinds the "neck" of the blank adjacent the bolster to the required amount; and then withdrawn outwardly slowly still in contact with the face of the wheel until the blade tip has been ground, the blade being rocked during withdrawal to adjust the taper of the blade to the lessening thickness of the blade from bolster to tip.

One object of the present invention is to enable the speed of the inward and outward strokes and the length of any desired dwell to be quickly and simply adjusted. Another object is to enable the outward stroke to be completed or, if desired, repeated at a speed independent of the normal speed at which this stroke is carried out; and also to interrupt and reverse the inward stroke at any point if required.

According to the present invention, the traverse mechanism comprises a traversing work support, stops adapted to limit the traverse, hydraulic means for effecting the traverse in both directions, a reversing valve mechanism for admitting fluid to the hydraulic means to effect the traverse stroke in each direction in turn, and pressure-responsive means to which fluid is also admitted during at least a traverse stroke in one direction, the pressure-responsive means being adapted to actuate the valve mechanism at the end of that stroke by the build-up of pressure in the fluid when the work support reaches the stop at the end of that stroke, thereby reversing the direction of traverse of the work support.

The reversal of the work-support traverse being effected by the build-up of pressure in the operating fluid circuit as the work-support reaches one or other of the stops, the length of the work-support stroke is independent of the

full length of the stroke of the hydraulic means and may be varied by adjustment of the position of the stops up to the full limit of that stroke.

The build-up of pressure in the pressure-responsive means may be delayed by the introduction of a needle or other throttle valve in the fluid circuit to the pressure-responsive means, to provide a dwell after the work-support reaches the stop at the end of its stroke before the traverse is reversed. The throttle valve may be adjustable to vary the length of the dwell.

A flow-control valve may be incorporated in the fluid circuit for at least one direction of traverse to permit a variation in the speed at which that 15 traverse stroke is effected. Manually-controlled means may be provided to by-pass a flow control valve to permit the stroke to be effected at a greater speed than when the valve is in operation, and such means may also be adapted to be brought into operation at any stage in the previous stroke so as to reverse that stroke independently of the pressure-responsive means, normally used to effect reversal, and to complete the first stroke at the greater speed.

25 The reversing valve is preferably incorporated in a single valve unit, being automatically reversed between the strokes by the pressure-responsive means also incorporated in the valve unit. The reversing valve may be manually controlled to initiate the movement of the work-support and such manual control preferably serves also to effect the by-passing of the flow-control valve as mentioned above.

The pressure-responsive means may comprise 35 a hydraulic cylinder, a piston of which positively effects reversal of the reversing valve on the build-up of pressure in the cylinder. The invention thus offers a very simple control unit; the single valve unit in which is combined the reversing cylinder and a single manual control member. The needle-throttle valve and flow-control valve may also be advantageously combined in the unit.

40 The hydraulic means for effecting the traverse of the work-support may comprise a single cylinder to ports at the opposite ends of which the fluid is admitted in turn to urge the work-support in first one direction and then the other, or separate cylinders may be used to effect the two strokes.

45 The invention also comprises hydraulic reversing valve mechanism embodying pressure-responsive reversing means as described above, particularly of the piston-and-cylinder type, together, if desired, with one or more of the aux-

iliary features: throttle-valve, flow-control valve, by-pass means, also described above, manually-controlled means, and unit construction.

One form of hydraulic traverse mechanism will now be described in greater detail as applied to the traversing of a work support in a cutlery grinding machine, although the traverse mechanism to be described is also applicable to other machines as previously mentioned. In the accompanying drawings:

Figure 1 is a plan view, partly in section, of a grinding machine set for the grinding of table and similar knives;

Figure 2 is a front elevation of the machine, partly in section on the line 2-2 of Figure 1;

Figure 3 is an end elevation of the machine on the line 3-3 of Figure 2;

Figure 4 is a diagram showing the approach of the blank to the grinding wheel;

Figure 5 is a section on the line 5-5 of Figure 2, on an enlarged scale;

Figure 6 is a section on the line 6-6 of Figure 5;

Figures 7, 8, and 9, are sections on the lines 7-7, 8-8 and 9-9 respectively of Figure 6; and

Figures 10 and 11 are views similar to Figure 6 at different stages in the operation of the machine.

The grinding machine embodies a work-support of the type fully described in Patent No. 2,481,918, dated September 13, 1949, and, referring in the first instance to Figures 1, 2 and 3, comprises a table 10 mounted on slide ways 11 (Figure 3) carried by a bed-plate 12 resting on the machine bed 13, so as to be movable to and fro in a direction generally transverse to the axis 14 of a cup wheel 15.

A work slide 16 is carried on the upper face of the table 10, and to it is secured an angle bracket 17, from which pivot brackets 18 protrude towards the wheel 15 to receive pivot pins 19 at each end of a work support 20 comprising a long block to the face of which is secured a pad 21 which supports a knife blade 22 to be ground. An arm 23 of the work support 20 carries a roller 24 resting on a former bar 25 to rock the support about the pivot pins 19 as the support is carried by the table 10 across the face of the wheel 15, so as to rock the blade 22 gradually as grinding proceeds from neck to tip, to allow for the varying taper of the blade arising from the gradual thinning of the back edge of the blade in the direction of the tip. The former bar is adjustable about a pivot 26 (Figure 3) on a mounting 27 by a setting screw 28, out of line with the pivot 26, and is clamped in adjusted position by a bolt 29. The mounting 27 is slidable vertically on a support bracket 30 upstanding from the bed-plate 12 and is adjustable for height by a screw 31.

The axis 14 of the cup wheel 15 is shown inclined (at about 10°) to the normal to the path of the table 10, and the face 32 of the wheel is inclined inwards to the same amount so as to lie parallel to the path of the table, the movement of the table 10 carrying the blade 22 across the left-hand side 33 of the wheel, with an idle movement in one direction (to the right in Figures 1 and 2) and a grinding movement in the reverse direction. The inward inclination of the face 32 of the wheel produces the desired slight outward curvature on the ground face of the blade 22. The machine may, however, be constructed with the table and work-holder reversed with respect to the wheel, in which case the work is carried across the right-hand side of the wheel,

to enable the other side of the blade blank to be ground; and, in fact, machines are generally used in pairs, one left-hand and one right hand.

For some purposes (the grinding of plane or hollow-ground (e. g. shear-blade) surfaces), the axis 14 of the wheel may be normal to or inclined in the opposite direction to the normal to the path of the table 10, and adjustment of the relative inclination is provided for by pivoting the bed-plate 12 carrying the table 10 about a pin 34 screwing into the machine bed 13, the axis of the pivot pin lying vertically beneath the operative left-hand portion 33 of the wheel. The plate 12 is secured in adjusted position by a bolt 15 35 near the pivot pin 34 and two bolts 36 adjacent the front and left-hand edges of the plate, the bolts 34, 36 passing through slots 37, 38 in the plate 12 and screwing into the machine bed 13.

The slide 16 is mounted on slideways 40 carried by the table 10, the slideways running at 45° from right to left from the front to the back of the table and the slide 16 being held to the table 10 by washers 41 retained by lock nuts 42 on pins 43 projecting from the table 10 and passing through slots 44 in the slide parallel to the slideways 40. A plunger 45, carried by the slide 16 and also parallel to the slideways, is urged by a spring 46 into contact with an abutment 47 protruding from the table 10, so as to urge the slide 16 towards the front of the table.

A hydraulic cylinder 48 carried by the plate 12 between the slideways 11 for the table 10 runs parallel to the length of the table and the piston 49 is connected by a piston rod 49A to a lug 50 depending from the right-hand end of the table 10. Pressure oil admitted to one or other of ports 48A, 48B of the hydraulic cylinder 48 in turn, through flexible pipes 51A, 51B connected to a multi-way valve unit 52 (as will be described in detail later), causes the table 10 to move to and fro with any desired length of stroke.

Running lengthwise of the table 10 is a parallel slot 53, passing to the right-hand end of the table and breaking through a recess 54 near the middle of the table. A push-rod 55 closely fits the slot and a lateral arm 56 of the rod protrudes through the recess 54 beyond the front of the table. Opposite the arm 56, the rod is notched at 57 to form a land 58 leading by a cam slope 59 to the edge 60 of the rod. A follower roller 61 carried by the slide 16 depends into the recess 54 and is urged by the plunger 45 into contact with the rod 55.

The end of the rod 55 projects beyond the end of the table 10 and carries a plate 55A facing an adjustable stop 62 on a bracket 63 upstanding from the bed-plate 12. The plate 55A itself carries an adjustable stop 64 facing the edge of a cover plate 65 secured at the end of the table 10 over the push-rod 55. An adjustable stop 66 carried by a bracket 67 upstanding from the foot of the front slide-way 11 lies parallel to the length of the table 10 in line with the outer end of the lateral arm 56 of the rod 55.

In Figures 1 and 2, the table 10 is moving on its idle stroke to the right under the admission of oil through the left-hand port 48A of the hydraulic cylinder 48. The follower roller 61 bears on the land 58 in the notch 57 of the push-rod 55, the slide 16 thus lying in its nearest position to the front of the table 10. In this position the blade 22 lies clear of the wheel 15, as shown.

As the table 10 nears the right-hand end of its stroke the plate 55A on the end of the push-rod

55 meets the stop 62 (the actual position shown in Figures 1 and 2), and the push-rod is prevented from further motion to the right. The table 10 continuing its motion to the right, the follower roller 61 is caused to ride up the cam slope 59 of the now-stationary rod 55 and on to the edge 60 of the rod.

The slide 16 carrying the roller 61 is forced to follow the movement of the roller, and is thus pushed towards the rear of the table 10, by an amount equal to the lift of the cam, to bring the blade 22 into grinding contact with the wheel 15, the slide moving along the inclined slideways 40. During this movement, the spring 46 is compressed on to the plunger 45.

On reaching the full lift of the cam slope 59, the follower-roller 61 comes to rest on the edge 60 of the rod 55, and remains urged against the rod by the pressure of the plunger 45, the whole length of the rod resting in the slot 53 providing a rigid backing against the thrust of the slide 16 laterally of the table 10.

When the cover plate 65 reaches the stop 64, the right-hand motion of the table 10 ceases (as will be described later) and at this moment the outside diameter of the wheel 15 makes grinding contact at the "neck" of the blade 22, i. e. against the bolster 68 (Figure 4), the blade having been brought against the face of the wheel by the movement of the slide 16 to the rear of the table 10. The operation of the hydraulic cylinder 48 now reverses (as will be described later) and the table 10 moves to the left, carrying with it the slide 16, which is locked to the table by the pressure of the follower roller 61 on the edge 60 of the rod 55.

The movement of the work up to this point may be closely followed by reference to Figure 4:

The blank (blade 22, bolster 68) as shown in full lines is moving to the right (arrow a) as in Figures 1 and 2, with the blade 22 parallel to, but clear of, the face 32 at the left-hand side 33 of the wheel 15.

When the push-rod 55 is held by encountering the stop 62, the table 10 continues to move by the amount shown by the chain-line containing the arrow b, and the cam 59 pushes the slide 16 (and therefore the blank) in a 45° direction as shown by the chain-line containing the arrow c. The component of the table movement and the slide movement is thus a movement along the chain-line containing the arrow d.

The blank has now reached the position shown in broken lines (22^a, 68^a), the blade 22 having one side in contact with the face 32 of the wheel, and the "neck" 68^b lying against the radiused edge 15^a of the wheel. At this point, the table 10 is reversed by the hydraulic cylinder 48 (arrow e), and grinding of the side of the blade 22^a continues from the completed neck to the tip of the blade.

During the grinding stroke, the pressure of the wheel keeps the rear side of the blade firmly against the pad 21. The accurate guiding of the table 10 by the slide-ways 11 and the pressure of the spring 46 through the slide 16 to the long edge of the slot 53 containing the push-rod 55 ensures that the blade follows an accurate line across the wheel 15, which may be repeated with equal accuracy if it proves necessary to send the blade a further time across the wheel. As a result, a highly finished ground surface is produced that calls for the minimum amount of glazing in a subsequent operation, as is usual with table and similar knives.

When the tip of the blade 22 reaches the face 32 of the wheel, the stop 66 meets the arm 56 to push the rod 55 to the right (relatively to the moving table 10), thus carrying the cam slope 59 under the follower roller 61. The pressure of the plunger 45 causes the roller 61 to push the rod 55 to the right (there being nothing to oppose this movement of the rod), and the roller 61 reaches the land 58 with a snap action. The slide 16 thus moves quickly towards the front of the table 10, and the blade 22 is withdrawn from the wheel, with no delayed contact that might mar the ground surface of the tip of the blade.

The left-hand motion of the table 10 continues until the arm 56 of the rod 55, which has been displaced to the right-hand end of the recess 54 as the roller 61 reaches the land 58, again contacts the stop 66, when the motion ceases (as will be described later). The ground blade is now removed and replaced by a fresh blank, or, if necessary, the blade is left to undergo a further grinding cycle. Reversal of the operation of the cylinder 48 (as will be described later) again brings the mechanism to the position shown in Figures 1 and 2. The width of the recess 54 provides the necessary freedom of movement of the arm 56 relative to the table 10. The three stops 62, 64 and 66 enable the positions of the ends of the strokes and the rearward and forward movements of the slide 15 to be determined with precision in accordance with the length of the blade 22, in conjunction with the valve mechanism for the supply of oil to the cylinder 48 as will now be described.

The valve unit 52 (Figures 5 to 11) comprises a valve piston 70 which is hardened, ground and lapped into a valve bore 71 of a main rectangular block 72 mounted by bolts 72A on the back of a panel 13A secured to the front of the machine bed 13 (Figure 2) by bolts 13B. The piston 70 is circumferentially grooved at 73, 74, 75 and 76, the grooves 73, 74 and 76 being in communication with each other through holes 77 drilled radially from the bottoms of the grooves into a bore 78 (Figure 7) drilled axially in the piston from its right-hand end 79, the open end of the bore 78 being closed by a screwed plug 80. A piston rod 81 extends from the left-hand end of the piston through a bush 82 in an end plate 83 bolted to the block 72 by bolts 84, the end plate 83 being formed with a short spigot 85 engaging the end of the valve bore 71.

The right-hand end of the valve bore 71 is closed by an intermediate block 86 spigoted at 87 to fit the valve bore and bored at 88 axially with the valve bore 71 to receive a piston 89 which is an easy fit within the bore 88. The inner end of the piston 89 is rounded at 90 and the outer end is provided with a cup washer 91 closely fitting the bore 88. The cup washer is secured to the piston by a nut 92 on a rod 93 screwed into the end of the piston. The piston rod 93 projects into a recess 94 in the inner face of an end plate 95 spigoted at 96 to fit a counterbore of the piston bore 88. The end plate 95 and intermediate block 86 are secured to the main block 72 by bolts 97.

The valve bore 71 of the main block 72 has circumferential grooves 100, 101, 102, 103 and 104, the grooves 100, 103 being connected by the flexible pipes 51A, 52B to the ports 48A, 48B respectively of the hydraulic cylinder 48, unions at the ends of the pipe engaging threaded recesses 105, 105A drilled from the top face of the block 72 and breaking into the grooves 100, 103.

The grooves 102, 104 break into threaded recesses 106, 107 drilled from the rear of the block 72 to receive pipes 108, 109 (Figures 2 and 7) respectively connected to the oil pump and tank (not shown) housed at the foot of the machine bed. The pipe 108 from the pump is interrupted by a relief valve 108A adapted to pass oil from the pump direct to the tank, as will be described later.

Two holes 110, 111 are drilled from the bottom face of the block 72 into the valve bore grooves 100, 101, the holes breaking through a bore 112 drilled at right angles to the holes from the front face of the block, and the lower ends of the two holes being closed by screwed plugs 110A, 111A.

A circumferentially-grooved cylinder 113 (Figures 6 and 9) rotatably fits the bore 112, being lapped in position and being retained by square end plates 114, 115 secured by bolts 116, 117 to the front and rear faces respectively of the block 72, the inner faces of the end plates being formed with spigots 114A, 115A engaging the ends of the bore 112. A shank 113A extending from the front end of the cylinder 113 passes through a bore 114B of the front end plate 114 and projects beyond the latter to receive a cap 118 provided with a short control lever 118A. The end plate 114 is thick enough to provide a good length of bearing for the shank 113A in the bore 114B, the end plate projecting through a square aperture 13C cut in the panel 13A.

In line with the two holes 110, 111, the cylinder 113 is cut away at 119 to form the eccentric cross-section as shown in Figure 6, which in conjunction with the bore 112 forms a flow-control valve, the action of which will be described later.

A hole 120 drilled from the right-hand end of the block 72 parallel to the valve bore 71 breaks into the hole 111 just above the bore 112, and its outer end opens into a short groove 121 cut in the inner face of the intermediate block 86 at right angles to the hole 120.

Two parallel holes 122, 123 are drilled from the bottom face of the end plate 95 and open into the recess 94 (Figure 8). The rearmost hole 123 is counterbored at 124 to receive a ball 125 urged against the seating provided by the end of the counterbore by a spring 126 retained in position by a screwed plug 127 sealing the lower end of the counterbore, the ball 125 forming an escape valve for oil in the recess 94 as will be described later. The lower end of the hole 122 is sealed by a screwed plug 128.

A hole 129 drilled from the front face of the end plate 95 at right-angles to the two holes 122, 123 intersects the hole 122 and the counterbore 124 and extends slightly beyond the latter to break into a hole 130 drilled from the base of the groove 121 in the inner face of the end plate 95. The hole 129 is counterbored at 131 from the front face of the end plate 95 to the hole 122, the end of the counterbore being tapered down at 132 to the diameter of the hole 129 to form a seating for a tapered needle valve 133. The needle valve 133 is carried on the end of a screwed stem 134 threaded into the counterbore 131 and projecting through a hole 135 in the panel 13A to the front of the machine bed 13. The outer end of the stem 134 is formed with a saw cut 136 for screwdriver adjustment of the needle valve and a lock nut 137 on the stem serves to secure the needle valve in adjusted position. A protective cap 138 screws on to the projecting end of the stem 134. The needle valve 133 serves as the throttle valve to effect a "dwell" 75

at the end of the idle stroke of the table 10 before the working stroke is commenced, as will be described later.

A control lever 140 (Figures 2 and 5 and also shown in chain-line in Figures 6, 10 and 11) at the front of the machine is secured adjacent its lower end to the front end of a pivot pin 141 mounted in an integral pivot boss 142 of the panel 13A lined with a bush 143. Secured to the rear end of the pivot pin 141 is an upwardly extending forked lever 144, the two arms 145 of which carry studs 146 engaging a groove 147 (also Figure 6) in a cylindrical head 148 secured to the outer end of the rod 81 of the valve piston 78. The lower end of the lever 149 is formed with a chisel point 149 normally engaging a V-shaped notch 150 cut across the upper end of a plunger 151 vertically slideable in a mounting 152 secured to the panel 13A. The plunger 151 is bored at 153 from its lower end to receive a spring 154 held in compression by an adjusting bolt 155 screwed through the bottom of the mounting 152 and provided with a lock nut 156.

The normal vertical position of the control lever 140 is as shown chain-dotted in Figure 10, and in this position the table 10 is at the end of its left-hand motion with the work slide 16 withdrawn away from the wheel 15 and with the arm 56 of the push-rod 55 abutting the right-hand side of the recess 58 and the stop 66. To start the table 10 on its idle stroke to carry the knife blade 22 to the wheel 15, the control-lever is swung to the right (the position as shown in Figures 2 and 6) thus urging the valve piston 78 to the right-hand end of the valve bore 71 as shown in Figure 6. The control lever is held in this position by the upward thrust of the spring plunger 151, the chisel pointed end 149 of the lever having travelled up the V-shaped notch 150 of the plunger and come to rest with its face 157 engaging an inclined face 158 (Figure 6) at the upper end of the notch.

In this position of the valve piston 78, the piston groove 74 uncovers the valve bore grooves 101, 102 and admits oil under pressure from the pump (via the pipe 108) into the axial bore 78 of the piston through the radial holes 77 in the piston groove 74, and the oil is fed along the bore 78 into the piston groove 73 which uncovers the valve bore groove 100 thus completing the path of the oil to the left-hand port 48A of the hydraulic cylinder 48 through the pipe 51A. Oil is also admitted through the holes 111, 120, the grooves 121, the holes 130, 129, the needle valve 133 and the hole 122 into the recess 94 in the end plate 95 behind the piston 89.

The valve piston groove 75 uncovers the valve bore grooves 103, 104, thus connecting the right-hand port 48B of the hydraulic cylinder 48, through the pipe 51B, to the tank, via the pipe 109, to complete the return circuit for the oil at the right-hand side of the piston 49.

When the cover plate 65 contacts the stop 66 (as previously described), further movement of the table 10 to the right is prevented and pressure builds up in the input oil circuit, which as previously described is tapped through the adjustable needle valve 133 to the recess 94 behind the piston 89. (The latter has, on movement of the control lever 140 to the right, been pushed within the bore 88 (as shown in Figure 6) by the end 79 of the valve piston 78, the piston rod 83 projecting into the recess 94 preventing further adventitious movement of the piston 89 which

might otherwise bring the cup washer 91 out of the bore 88.)

When the pressure in the recess 94 has built up to a predetermined value, the axial force on the piston 89 is sufficient to overcome the resistance of the spring plunger 151 holding the control lever 140 in its right-hand position and the valve piston 70 is pushed by the piston 89 along the valve bore 11 to the position shown in Figure 10 where it is held by the chisel point 149 of the control lever engaging the notch 150 in the spring plunger, the spring plunger itself ensuring a quick snap-over to this position once the chisel point 149 of the control lever has been forced by action of the piston 89 over the crest of the inclined face 158 of the spring plunger.

The upward pressure of the spring plunger on the control lever is adjusted by the adjusting bolt 155 so that in the position of the lever in Figure 20 6 the normal working pressure of the oil in the recess 94 during the idle stroke of the table 10 is not sufficient to displace the valve piston 70, and the time taken, from the end of the right hand motion of the table 10, for the pressure in the recess 94 to build up sufficiently to displace the valve piston is determined by adjustment of the needle throttle valve 133. Thus, a "dwell" may be provided after the blade 22 has been presented to the wheel 14 (as previously described) to ensure satisfactory grinding of the "neck" 68a of the blade before the motion of the table 10 is reversed to effect the grinding of the face of the blade.

When the valve piston 70 is pushed by the piston 89 to the position shown in Figure 10, the valve piston groove 75 now uncovers the valve bore grooves 102, 103, thus connecting the oil under pressure from the pump direct to the right-hand port 48B of the hydraulic cylinder 48, through the pipe 51B, to urge the table 10 to the left on its grinding stroke.

The valve bore groove 100 is covered by the valve piston 70 so that the only outlet from this groove for the oil on the left hand side of the piston 49 returning to the tank through the pipe 51A is along the hole 110 leading to the flow-control valve 119. The oil passes into the flow-control valve bore 112 and along the hole 111 to the valve bore groove 101 which is now uncovered by the piston groove 74. The oil passes through the radial holes 77 into the axial bore 78 of the piston and along the latter to the piston groove 76, which now uncovers the valve bore groove 104, thus completing the return circuit for the oil to the tank through the pipe 109.

The flow control valve governs the return flow of the oil to the tank and so governs the speed of the grinding stroke of the table 10 to the left, thus enabling this grinding stroke to be effected at any desired slower rate than the previous idle stroke of the table, which being effected at the maximum fluid delivery of the pump rapidly moves the blade to be ground inwardly and idly across the face of the grinding wheel. The flow control valve is shown in Figures 6, 9, 10 and 11 at its zero setting, i. e. with the valve eccentric 119 turned (by the lever 118A) to a position in which it seals completely the entrance of the bore 110 into the valve bore 112. When the valve is turned to the position shown in chain-dotted lines in Figure 6, it is at its maximum flow setting when the speed of the grinding stroke of the table 10 is effected at the same rate as the idle stroke.

The bore 120 leading from the recess 94 opens into the bore 111 leading from the flow control valve so that the pressure of the oil in the recess falls when the piston 89 has pushed the valve piston 70 to the reversing position.

When the grinding stroke is completed and the arm 56 of the push-rod 55 is forced against the stop 66 (as previously described), pressure builds up in the oil passing from the pump to the hydraulic cylinder 48 and the oil is passed from the pump direct to the tank by the relief valve 108A. The relief valve 108A does not operate until the pressure in the oil has built up to a value greater than that required to operate the piston 89 at the end of the idle stroke. If the blade is satisfactorily ground, another blank is inserted in position on the pad 21, and the cycle is repeated by again swinging the control lever 140 to the right, i. e. to the position shown in Figure 6.

In swinging the control lever to the right to initiate a further idle stroke, the piston 89 is forced back within the bore 88 by the valve piston 70 and the oil in the recess 94 behind the piston is rapidly ejected from the recess along the hole 123 as the pressure in the oil builds up sufficiently to displace the escape-valve ball 125 against the resistance of the spring 126. The throttle valve 133 is thus by-passed and the oil passes along the bore 130, groove 121, and bores 120, 111 into the valve bore groove 101. During the initial part of the movement of the control lever to the right, the groove 101 is still connected to the tank through the piston groove 74, axial bore 78, piston groove 16 and valve bore groove 104, so that oil from the recess 94 is fed to the tank. During the latter part of the movement of the lever however the groove 101 is connected to the valve bore groove 102 (as the valve piston groove 74 uncovers the latter) and therefore to the pump, and the oil from the recess 94 is fed into the oil from the pump, the pressure being greater than that of the oil from the pump.

The pressure of the oil in the recess 94 required to operate the escape-valve 125 is greater than the pressure required to reverse the valve piston 70 (as previously described), so that no leakage occurs through the escape-valve as the pressure in the recess 94 builds up at the end of the idle stroke.

If, during the grinding stroke of the table 10, or at the end of the stroke, it is desired to withdraw the blade being ground rapidly from the wheel, the control lever 140 is swung to the left to the position shown in Figure 11 where it is held manually, the chisel end 149 riding up the wall of the V-notch 150 in the spring plunger 151 to the position as shown; so that on eventual release of the lever, the spring plunger will automatically return the lever, and therefore the valve piston 70, to its normal central position.

With the control lever held to the left, the valve piston 70 is carried to the left end of the valve bore 71, as shown in Figure 11, in which the piston groove 75 still uncovers the valve bore grooves 102, 103, thus retaining the direct pump connection to the right-hand port 48B of the hydraulic cylinder 48, but in which the return circuit for the oil from the left-hand port 48A through the pipe 51A by-passes the flow control valve 119, the oil passing directly into the piston groove 74, which now uncovers the valve bore groove 100, through the radial holes 77 into the axial bore 78 of the piston, along the bore 78 to the piston groove 76 which now uncovers the valve bore

groove 104, thus completing the return circuit to the tank through the pipe 109.

The outward stroke is thus completed at a greater speed than the normal working stroke with the control lever in its central position and the flow-control valve in operation. This bypassing of the flow-control valve may be used to effect a rapid completion of the working stroke once the blade 22 has been fully ground, i. e. when the arm 56 of the push-rod 55 first meets the stop 66 to effect the withdrawal of the blade from the wheel, so that the blade may be quickly removed and replaced by another blank. If desired the rapid left-hand motion of the table 16 may be used for effecting a second (generally light) passage of a ground blade across the wheel if this is needed, the control lever being first swung to the right to effect the idle inward stroke as previously described, and then, after it has been returned to its central position by the reversing plunger 89, being swung to the left to effect a rapid grinding stroke.

Since the control lever may be swung to the left at any stage in the cycle of the table 16, the latter may be readily brought back rapidly to its normal position, if, for example, the blank is seen to be in wrong position on the pad 21, before the idle stroke would normally have been completed and the blank presented to the wheel.

Any oil leaking to the left-hand side of the valve piston 70 during the operation of the machine is returned to the tank via a bleed hole 160 (Figures 6, 10 and 11) drilled in the end plate 83, the bleed hole running into a screwed recess 161 in the bottom face of the end plate to receive the union at the end of a pipe 162 leading to the tank. Any leakage to the right-hand side of the valve piston is forced along the bore 88 (the piston 89 being a free-fit in the bore as previously described), past the cup-washer 91 and into the recess 94 when the control lever is swung to the right to initiate an idle stroke of the table (as previously described).

The hydraulically-controlled traverse mechanism as described produces a high-quality finish to the ground surfaces of the blade, with consequent advantage at the glazing stage to which many blades are next subjected. In addition, the simple adjustment of feed rate and length of "dwell" at the end of the idle stroke to accord precisely with the size and type of blank to be ground assists in imparting a good finish, as well as conducing to high output.

What I claim is:

1. A hydraulic traverse mechanism for work-supports in grinding and other machines, comprising a traversing work-support, hydraulic means for effecting the traverse in both directions, pressure-responsive means, a reversing valve connected to the hydraulic means and the pressure-responsive means, a stop for positively limiting a traverse stroke in one direction whereby when the stop is encountered pressure build-up in the hydraulic means actuates the pressure-responsive means to operate the reversing valve to bring about a stroke of the work-support in the other direction, and manual means for moving the reversing valve in one direction to initiate a traverse stroke that is automatically reversed by the operation of the pressure-responsive means at the end of that stroke, said manual means also being adapted to move the reversing valve in the opposite direction to produce a reverse stroke independently of the pressure-responsive means.

2. A traverse mechanism as in claim 1, com-

prising a throttle valve between the reversing valve and the pressure-responsive means to delay the response of the latter to the build up of pressure, thereby producing a dwell before commencement of the reverse stroke.

3. A traverse mechanism as in claim 1, comprising a flow-control valve to reduce the speed of the traverse stroke effected by operation of the pressure-responsive means, and a by-pass to cut out the flow-control valve in a stroke in the same direction effected by operation of the manual means.

4. A traverse mechanism for work-supports in grinding and other machines, comprising a traversing work-support, stops adapted to limit the traverse, hydraulic means for effecting the traverse in both directions, a unitary reversing valve structure for admitting fluid to the hydraulic means to effect a traverse stroke in each direction

15 in turn, said valve structure including a valve cylinder with an inlet port receiving pressure fluid, two outlet ports connected respectively to pressure and exhaust conduits leading to said hydraulic means and an exhaust port, a piston

20 valve movable in the cylinder so as to put the inlet port in connection with one outlet port and the other outlet port in connection with the exhaust port, pressure-responsive means in connection with one of the outlet ports, and comprising a cylinder coaxial with the reversing valve cylinder and a piston slidably so as to operate the piston valve on build-up of pressure, to produce a reversing movement of the valve on build-up of pressure in the circuit to which that outlet port is connected thereby reversing the direction of movement of the hydraulic means.

5. A traverse mechanism according to claim 4, wherein the reversing valve structure also includes a throttle valve between the pressure-responsive means and the outlet port to which the latter is connected, so as to control the rate of build-up of pressure thereby provide a dwell before the reversal of the piston valve.

6. Hydraulic reversing valve mechanism comprising a valve cylinder with an inlet port, two outlet ports, and an exhaust port, a piston valve movable in the cylinder to put the inlet port in communication with one outlet port and the other outlet port in communication with the exhaust port, pressure-responsive means comprising a cylinder coaxial with the reversing valve cylinder and a piston connected to the piston valve, said means being connected to one outlet port so as to subject the piston to build-up of pressure in the circuit to which that outlet port is connected, thereby operating the reversing valve.

7. Hydraulic reversing valve mechanism as in claim 6, comprising manual means for operating the reversing piston valve in a direction opposite to its operation by the pressure-responsive means, and means for holding the manual means after its operation of the reversing piston valve, the pressure-responsive means operating to overcome the holding means when build-up of pressure effects reversing of the reversing piston valve.

8. Hydraulic reversing valve mechanism comprising a valve cylinder with an inlet port, two outlet ports, and an exhaust port, a piston valve movable in the cylinder so as to put the inlet port in communication with one outlet port and the other outlet port in communication with the exhaust port, and pressure-responsive means in communication with one of the outlet ports, said means being connected to the piston valve to produce a reversing movement of the valve on

13

build-up of pressure in the circuit to which that outlet port is connected, manually-controlled means for operating the piston valve by a movement in one direction, means for holding the manually-controlled means in one position after its operation of the piston valve, the pressure-responsive means operating to overcome the holding means under build-up of pressure, a flow-control valve connected to one of the outlet ports to reduce the delivery of hydraulic fluid through that port, and a by-pass for the flow-control valve, the manually-controlled means being movable to another position to operate the by-pass and increase the delivery of hydraulic fluid.
